UNITED STATES PATENT OFFICE.

CLYDE L. CRAIG, OF WASHINGTON COURT HOUSE, OHIO.

FOLDING CHAIR.

Application filed January 20, 1921. Serial No. 438,632.

To all whom it may concern:

Be it known that I, CLYDE L. CRAIG, a citizen of the United States, residing at Washington Court House, in the county of 5 Fayette and the State of Ohio, have invented certain new and useful Improvements in Folding Chairs, of which the following is a specification.

This invention relates to a chair which 10 when folded will lie compactly in substantially a single plane, and which when adjusted for use will remain rigidly in open position, and will be so balanced in respect to its center of gravity that it will not be 15 easily tipped over.

While the chair shown and described is designed more especially for the use of children I do not wish to be limited to any particular size.

20 The invention consists in the novel features of construction hereinafter described, pointed out in the claims, and shown in the accompanying drawings, in which:—

Figure 1 is a plan view with the chair in 25 open position.

Figure 2 is a section on the line 2—2 of Figure 1.

Figure 3 is an edge view of the chair folded.

30 In the drawings 1 designates the chair back, constructed in any desired manner and of any desired design. The back 1 is provided with side members 2 which extend downwardly below the back portion and 35 also below the seat portion. Pivots secured to the inner faces of these side members, and just below the lower end of what may be considered the back portion of the chair are curved or angled metal brackets 40 3, the point of connection between said brackets and the side members being indicated at 3^a. The chair is provided with front supporting legs 4 and rear supporting legs 5, the legs 4 and 5 intersecting and 45 being connected by a pin 6. The rear legs 5 are also pivotally connected to the side members 2 as at 2^a.

Special attention is called to the fact that the pivot pins 6 are off center with respect 50 to the rear legs 5, being in advance of the major axis of said legs, while the pivotal connection at 2^a is to the rear of the central longitudinal line of the legs 5 and in advance of said line with respect to the side 55 members 2. This not only allows the chair to fold very compactly, as indicated in Fig-

ure 3, but gives a firmness and rigidity to the chair when unfolded for use not obtainable in the folding chair of ordinary construction.

The front supporting legs 4 are connected adjacent their lower ends by cross braces 7, and the rear legs are connected by cross braces 8 adjacent their upper and lower ends respectively.

60 A rod 9 connects the upper portions of the legs 4 said rod also passing loosely through the brackets 3.

A seat 10 is pivotally mounted on said rod the sides of said seat fitting between the 70 brackets 3 and being fastened thereto.

When in position for use the seat 10 rests on the upper ends of the legs 5. A chair so constructed is not easily tipped over, being well balanced, and affords a firm solid seat.

75 In the chair of the usual construction a child climbing on to the seat will in most cases overbalance the chair and it will tilt forward, often causing it to slide backward throwing the child to the floor. Or if, in 80 the case of the full size adult's chair, a chair of the usual type is stood upon it is likely to tip over. By my construction all tipping tendencies of the chair, in either large or small size is avoided. This is due to the 85 fact that the front edge of the seat is in the same perpendicular plane as the forward ends of the front legs, the said legs resting on the floor in a vertical plane with the front of the seat. At the same time the rear 90 legs extend farther back than the seat. The points of the floor on which the legs rest form the corners of a substantially square base and the entire seat lies within this base.

95 What I claim is:—

1. In a folding chair having a back, intersecting front and rear legs, and a seat, means for pivotally connecting the rear legs to side members of the chair back, curved metal brackets pivotally connected respectively to 100 said back and to the front supporting legs, and a rod connecting the upper ends of the front supporting legs and forming a pivot for the seat.

2. In a folding chair comprising a back 105 having downwardly extending side members, intersecting front and rear legs, said rear legs being pivotally connected to the lower end portions of the side members of the back, angled metal brackets pivotally 110 connected to said side members, a rod connecting the front legs and pivotally con-

necting said legs to said brackets, and a seat positioned at its rear end between said brackets and fastened rigidly thereto, the seat being pivotally mounted on said rod, and resting when in open position on the upper ends of the rear legs.

3. In a chair, a back having downwardly extending side members, intersecting, pivoted front and rear legs, the pivotal connection between said legs being off center with respect to the rear legs, means for directly pivoting the rear legs to the side

members of the back, said means being located off-center with respect to both the rear legs and said side members, angled metal brackets pivotally connected to the side members of the chair back, a seat mounted between and fastened to said brackets, and common means for pivotally connecting the said seat and the said brackets to the front 20 legs.

In testimony whereof I affix my signature.

CLYDE L. CRAIG.
